INVENTOR:

Henry P. Kraft

By Attorneys,

Fraser, Turf & Myers

UNITED STATES PATENT OFFICE.

HENRY P. KRAFT, OF RIDGEWOOD, NEW JERSEY.

DUST CAP FOR TIRE VALVES.

Application filed July 17, 1919. Serial No. 311,459.

To all whom it may concern:

Be it known that I, HENRY P. KRAFT, a citizen of the United States of America, residing in Ridgewood, in the county of Bergen and State of New Jersey, have invented certain new and useful Improvements in Dust Caps for Tire Valves, of which the following is a specification.

This invention relates to dust caps for tire valves, and aims to provide certain improvements therein.

The present invention is directed to the type of dust cap adapted to be held on the tire valve stem by catches which yield in either direction as the cap is pushed on and off of the valve. By this means the cap requires no screwing motion to connect it to the valve, it being held by the resilient engagement of the catch or catches.

According to the present invention the catch members are preferably formed of wire having bent-in portions adapted to yieldingly engage the threads of the valve casing. By this means a simple and effective construction may be obtained. The invention also includes certain other features of novelty which will be hereinafter more fully described.

Referring to the drawings, which illustrate several forms of the invention,—

Figure 1 is an elevation of the cap.

Fig. 2 is a diametrical section thereof on an enlarged scale, showing a valve casing in elevation.

Fig. 3 is a section of Fig. 2 on the line 3—3.

Fig. 4 is a view partly in elevation and partly in section taken at right angles to Fig. 2, looking to the right.

Fig. 5 is a sectional view of a modification.

Referring to the drawings, let A indicate the cap as a whole. It best comprises a cap portion B and a foot portion C, the foot portion C serving to house the spring catch member D and to provide a better finish for the cap.

The spring catch member D preferably comprises a ring of wire of proper resilience, the two ends of which are bent inwardly as shown at E E' to form spring catches adapted to yieldingly engage the threads of the valve casing. These catches are preferably separated sufficiently, so that

if the flat F of the valve casing G should happen to coincide generally with the catches, at least one of the latter will engage the thread.

In the construction shown the cap member is provided with a bead H at a point slightly above its bottom J, thus forming a recess below it in which the catch member D is located. The foot portion is so formed as to constitute with the recess a chamber which is closed throughout except at an opening K (best shown in Fig. 4) through which the catch portions E E' project inwardly to engage the valve casing. The foot member preferably comprises a bottom portion L, side portion M and top portion N, the top portion being turned over the bead H, so as to hold the foot in place.

In Fig. 5 I have illustrated two catch members D' D'', one of which has its catch portions on one side and the other on the opposite side, so that they project inwardly toward each other at diametrically opposite points. The arrangement of catch members, however, may be varied at will.

By the present construction a very cheap and efficient form of quick detachable cap is provided, the spring grip upon the valve casing being sufficient to hold the cap in its closed or applied position.

While I have shown and described one form of the invention, it will be understood that changes may be made therein without departing from the spirit of the invention.

What I claim is:

1. A dust cap having a cap portion, a foot portion in fixed relation with a part of said cap portion and cooperating therewith to form an annular recess, an opening in said cap portion, and spring catch means in said recess and having engaging means projecting inwardly through said opening.

2. A dust cap having a cap portion, a foot portion co-operating therewith to form an annular recess, said cap portion having an opening at its lower end, and a circular spring wire arranged in said recess, and having its ends bent inwardly through said opening to engage the threads of the valve casing.

In witness whereof, I have hereunto signed my name.

HENRY P. KRAFT.
